UNITED STATES PATENT OFFICE.

JOHN M. BRADLEY AND CHARLES F. PIKE, OF PHILADELPHIA, PENNSYLVANIA,
ASSIGNORS TO THE SAFETY EYEGLASS COMPANY, OF WILMINGTON, DELA-
WARE, A CORPORATION OF DELAWARE.

EYEGLASS-CASE.

1,328,646.

Specification of Letters Patent.

Patented Jan. 20, 1920.

Application filed April 13, 1918. Serial No. 228,454.

To all whom it may concern:

Be it known that we, JOHN M. BRADLEY and CHARLES F. PIKE, citizens of the United States, residing at Philadelphia, in the county of Philadelphia and State of Pennsylvania, have invented certain new and useful Improvements in Eyeglass-Cases, of which the following is a specification.

This invention relates to eyeglass cases and has for its object to obviate and overcome the disadvantages and inconveniences attendant upon the use of the cases now in use owing to their overweight and bulk, and to construct eyeglass cases of a weight as light as possible with due regard to safety and efficiency.

A secondary object in so constructing eyeglass cases is to permit of their being made of precious metals or other valuable materials without unduly increasing the cost or sacrificing their utility.

With these objects in view, the invention consists in the improved construction, arrangement and combination of parts comprising an eyeglass case, hereinafter fully described and afterward specifically claimed.

In order that the construction and operation thereof may be readily comprehended, we have illustrated an improved embodiment of our invention in the accompanying drawings, and will now proceed to fully describe the invention, having reference to said drawings, in which—

Figure 1 represents a view of our invention in front elevation;

Fig. 2, a view of the same in side elevation;

Fig. 3, a view in end elevation;

Fig. 4, a view in front elevation of the cover of the case;

Fig. 5, a view, in side elevation of the cover;

Fig. 6, a view, in end elevation of the cover, and

Fig. 7, a view of a modification, in front elevation.

Like reference characters mark the same parts wherever they appear in the several figures of the drawings.

In the present invention the eyeglass case is composed principally of wire which may be of ordinary or precious metal according to the taste of the user, and in either case the weight will be greatly reduced from that of ordinary cases, without detracting from its beauty, strength or efficiency.

In the present instance the main body or support comprises an outer frame 10 of suitable wire, bent to the form desired, comprising the sides 11, the reduced rounded off top 12, and the approximately V-shaped lower portion 13, said outer pieces being joined by crossed wires 14 and longitudinal wires 15, all securely soldered or otherwise secured together to form a flat, substantially rigid, sheet-like structure. In the upper cross-wire 14^a is provided a backwardly and downwardly bent hook 16 to be entered into a pocket, button-hole, or other opening in a garment.

One or more of the cross wires, as 14^a, 14^b, may be bent into the form indicated at 17 in Fig. 3, to receive the eyeglass and prevent its lateral displacement. To the lower end may be soldered, or otherwise secured a reel, shown in dotted lines in Figs. 1 and 2, at 19.

The wires of which the case is constructed may be covered with any suitable material, ornamental or plain, to protect the glasses, and at 20, in Figs. 4, 5 and 6, we have shown a lining which may be secured inside the cases, if desired, for the same purpose.

In Fig. 7, we have shown a case constructed entirely of wire, but of a somewhat modified form, in which there are main or side wires 21, bent at the top to form a hook 22 to engage in a pocket or other opening in a garment, while at their lower ends they are bent to form a ring 23, from which project radial bends 24 forming fingers to grasp and support a reel, as shown in dotted lines.

Lateral supports 25 are secured to the main or side wires, having their outer ends bent at 26, to engage and prevent lateral displacement of the glasses. The side wires, hook, lateral supports and reel-supporting fingers may be formed of a single piece bent

to a suitable form, as seen in Fig. 7, and when the fingers are used, the reel may or may not be soldered to the case, as desired.

Having thus fully described our invention, 5 what we claim as new and desire to secure by Letters Patent of the United States, is:

1. An eyeglass case composed of a skeleton frame or sheet of wires and provided with a hook to engage an opening in a garment, and with a reel at its lower end, the 10

wires being bent to form fingers to embrace and support the reel.

2. An eyeglass case composed of a single piece of wire bent to form side wires, a hook, lateral supports, and fingers to embrace and hold a reel. 15

In testimony whereof we affix our signatures.

JOHN M. BRADLEY.
CHARLES F. PIKE.
